J. L. COX

PROJECTILE

FILED JUNE 1, 1920

FIG. 1.

FIG. 2.

FIG. 3.

WITNESS:

Bob Mitchell.

FIG. 4.

John L. Cox
BY
Frank D. Basser
ATTORNEY.

UNITED STATES PATENT OFFICE.

JOHN L. COX, OF PHILADELPHIA, PENNSYLVANIA.

PROJECTILE.

Application filed June 1, 1920. Serial No. 366,474.

To all whom it may concern:

Be it known that I, JOHN L. COX, a citizen of the United States, residing at Philadelphia, county of Philadelphia, and State 5 of Pennsylvania, have invented a new and useful Improvement in Projectiles, of which the following is a full, clear, and exact description, reference being had to the accompanying drawings, which form a part of this 10 specification.

In the attack of thick armor by armor-piercing projectiles it is found, as the angle of incidence of the projectile's axis with the normal to the plate's surface increases from 15 zero to twenty degrees (the greatest angle at which calibre thick, modern hard-faced armor plates are regularly pierced today without destruction of the projectile), that the transverse stresses upon the body of the 20 projectile increase rapidly and soon reach a point which the steel is unable to resist, even in the highly treated condition usually employed in projectiles, and rupture occurs. To increase the resistance of shells 25 to such stresses and other stresses and shocks is the object of my pending applications, Serial No. 311,325, filed July 16, 1919, and Serial No. 375,426, filed April 22, 1919.

As the angle of penetration increases beyond twenty degrees the conditions are still 30 harder, and it is necessary to adopt other measures to prevent the breaking off of the base of the projectile, which generally occurs through the forward undercut of the band 35 score. The prevention of this action is the object of the present invention.

When an inclined impact occurs on an 40 armor plate the arrest of the tangential component of the motion of the projectile's point with relation to the plate's surface causes the projectile to tend to right itself and produce perforation normal to the surface. At 45 high angles the righting is only partial; the projectile takes a diagonal path, and on emerging upon the opposite side tends further to right itself, increasing the before-mentioned heavy transverse stresses upon its body near the base. This pressure is sufficient to cold-draw out, for one and one- 50 quarter inch or more, the rear corner of the projectile's body. Were the pressure re-

moved, transverse fracture of the rear body would not occur.

My invention consists in fashioning the exterior portion of the projectile's body adjacent to the base, of a separate ring of metal, so formed as readily to detach itself upon unilateral pressure at the rear and thus reduce the diameter of the projectile's base and permit partial righting of the shell 60 about a transverse axis tangential to one side.

The detachable ring should have an external contour the same as that of the external wall of the corresponding part of a 65 standard shell, but the inner wall of the ring and the rear of the projectile's body beneath the ring should taper toward the base. The ring may extend from the base for a variable distance toward the point but preferably at least as far as the band score. The theoretical form of this taper is an ogival and this form may be employed, but in practice it is generally preferable to use chiefly a tangent to this curve; or an approximation 70 to the curve may be made by offsets, tangents and offsets, or in any other convenient way.

Attachment of the ring to the projectile's body may be made by screw threads, by a 80 shrinkage fit, by pinning, or in any other convenient manner.

Preferred embodiments of the invention are shown in the accompanying drawings, in which—

Fig. 1 is a side view of the projectile.

Fig. 2 is a longitudinal section through the rear of a projectile from the axis to one outer wall, one embodiment of my invention being shown.

Fig. 3 is a view, similar to Fig. 2, of another embodiment.

Fig. 4 is a view, similar to Figs. 2 and 3, but across the entire diameter, of another embodiment.

The body of the shell *a* is provided with the usual band *b*. In Fig. 2 the exterior portion of the projectile body from the band-score to the base comprises a ring *c*. The inner end of this ring is screw-threaded to 100 the projectile body at *d* and abuts against a shoulder *e* on the body and the lower edge

of the band *b*, which, preferably, extends slightly beyond the shoulder *e*, as shown. From the lower end of the screw thread toward the base of the projectile, the projectile body and the close fitting inner wall of the ring is tapered, as at *f*, toward the axis of the projectile and to a point close to the base.

In Fig. 3 h represents the projectile body, 10 i the band and j the detachable ring. In this construction, the taper is formed of a series of offsets m connected one with another by slight tapers n , and the ring has a shrinkage fit on the projectile body.

15 In Fig. 4 o represents the projectile body, p the band and r the ring, which, in this construction, is secured to the projectile body by pins s . The shape of the taper is an ogival, the center of the radius of longitudinal curvature along any arc x being a point y on the projectile diametrically opposite such arc, but forward thereof, preferably near the center of the band score, as shown in the figure.

25 The embodiments of my invention shown and described are only illustrative, my invention not being limited to the specific details shown.

Having now fully described my invention,
30 what I claim and desire to protect by Letters Patent is:—

1. A projectile comprising a body having its rear end open to receive the base plug, a band surrounding and contacting with the body, the body behind and partly beneath the band being of reduced diameter, a separable base ring surrounding the body behind and partly beneath the band and conforming on its outer surface approximately to the normal form of the rear of a projectile body, and means securing the base ring to the body rendering the ring detachable on impact, whereby on high angular impact against an armor plate with resultant detachment of the ring and reduction in diameter of the base, the projectile may partially right itself about a transverse axis tangential to one side and thereby avoid rupture of the projectile at the base.

50 2. A projectile comprising a body having its rear end open to receive a base plug, a band surrounding and contacting with the body, the body behind and partly beneath the band being of reduced diameter, the reduced diameter portion being further contracted in diameter toward the base, a separable base ring surrounding the body behind and partly beneath the band and conforming on its outer surface approximately to the normal form of the rear of a projectile body, and means securing the base ring to the body rendering the base ring detachable on impact.

3. A projectile comprising a body having
65 its rear end open to receive the base plug, a

band surrounding and contacting with the body, the body behind and partly beneath the band being of reduced diameter, the reduced diameter portion being tapered toward the base, a base ring surrounding the body behind and partly beneath the band, abutting walls of said ring and body being tapered inward toward the base, and means securing the base ring to the body for only a part of its length rendering the base ring detachable on impact. 70 75

4. A projectile comprising a body having its rear end open to receive the base plug, a band, the body, from beneath the rearward portion of the band, rearwardly, being in part of a reduced diameter, and in part of a substantially tapered form, and a separable ring conforming on a portion of its interior surface substantially to the form of the rear of the projectile's body and on its exterior surface to the normal form of the rear of the projectile's body, including therein a portion of the band score, said ring being shaped to leave the base plug opening unobstructed so as to permit the application of the ring and band independently of the base plug. 90

5. An armor piercing projectile having a body, a rotating band, and a separable frangible base ring, the seat for the band being partly formed in the metal of the projectile body and partly in the metal of the frangible base ring, the outer contour of the base ring forming part of the ordinary contour of the projectile, while the inner contour is in part of substantially tapered form with the smaller diameter towards the base of the projectile, the body of the projectile being substantially in contact with the ring throughout the length of the ring. 100 105

6. An armor piercing projectile comprising a body having its rear end open to receive the base plug, a rotating band and a separable base ring, the rear end of the body provided with a seat having a rearwardly facing shoulder and a portion of reduced diameter, said ring surrounding the body for at least that portion of the length of the body to the rear of the band and abutting against said shoulder and positively prevented from forward movement, said ring being frangibly secured to the body for only a portion of that part of the length of the body which it surrounds and conforming on its outer surface to the normal exterior contour of the projectile, said ring being shaped to leave the base plug opening unobstructed so as to permit the application of the ring and band independently of the base plug. 110 115 120

7. An armor piercing projectile comprising a body, a rotating band secured to the body and a separable base ring, the rear end of the body provided with a seat having a rearwardly facing shoulder rearwardly beyond which the band extends and a portion 130

of reduced diameter, said ring surrounding the body throughout that portion of the length of the body to the rear of the band and extending also within the band seat and 5 abutting against said shoulder and positively prevented from forward movement, said ring being frangibly secured to the

body and conforming on its outer surface to the normal exterior contour of the projectile.

In testimony of which invention, I have hereunto set my hand, at Philadelphia, Pa., on this 29th day of May, 1920.

JOHN L. COX.
